CLAIM

The ornamental design for a noise barrier as shown and described.

DESCRIPTION

FIG. 1 is a top perspective view of a noise barrier according to the present invention shown in a broken line environment of use forming no part of the claimed design;
FIG. 2 is a rear view of the noise barrier of FIG. 1;
FIG. 3 is a bottom view of the noise barrier of FIG. 1;
FIG. 4 is a front view of the noise barrier of FIG. 1;
FIG. 5 is a bottom rear perspective view of the noise barrier of FIG. 1;
FIG. 6 is a side view of the noise barrier of FIG. 1;
FIG. 7 is a top view of the noise barrier of FIG. 1;
FIG. 8 is a side view of the noise barrier of FIG. 1;
FIG. 9 is a detailed view of a portion of FIG. 3;
FIG. 10 is a detailed view of a portion of FIG. 6;
FIG. 11 is a detailed view of a first portion of FIG. 7; and,
FIG. 12 is a detailed view of a second portion of FIG. 7.
The dot-dash broken lines represent boundaries of the claimed design and form no part thereof.

1 Claim, 8 Drawing Sheets
